DES. 2287

Garrison Smith & Henry Brown, of Philadelphia, Pa.

Assignors to

J. Abbott & Noble, of the same place.

Letters Patent No. 2287 Date Mar. 24, 1866.

Ante-dated Feby 27, 1866.

Design for the plates of a Cook Stove

The schedule referred to in these Letters Patent & making part of the same

To all whom it may concern:

Be it known that we, Garrison Smith, and Henry Brown, of the City and County of Philadelphia State of Pennsylvania have invented or produced a new and original design for plates of the "Noble Cook" cook Stove and we do hereby declare the accompanying Drawing with the following explanation of the same to form a full, clear and exact description of the said Design.

On the accompanying drawing.

To the front plate A. are hung two doors B. each of which is edged with a plain moulding a. and has in the centre an ornamental figure d. of the form shown in the drawing.

On the plate near each door is an ornamental figure f. and at each edge of the plate is an ornamental moulding c.

Near the upper edge of the plate is an oblong panel on the face of which are ornamental figures i. and below the panel are the words "Noble Cook".

To the side plate C. are hung two doors D. D' each of which is bordered by a plain moulding a' and to a raised panel E. on the side plate is hung a door F. the moulding and ornaments on which are similar to those on the door B.

DS. 2287

2

More side of the panel B is an ornamental edging f and near the edges of the plate C are ornamental figures g h i, and on the top of the plate are the words "Noble Cook" below which is an ornamental heading j. At the lower part of the plate C is an ornamental panel k containing the words "Abbott & Noble, Phila."

The rear portion of the base plate A is higher than the front of the same, as shown in the drawing and at each side edges is a plain moulding m.

In the centre of the back plate I is an ornamental figure T.

We claim

The design for the plates of a cook stove, termed the "Noble Cook" substantially as shown in and by the accompanying drawing. In testimony whereof we have signed our names to this specification in the presence of two subscribing witnesses,
